United States Patent Office.

DUANE DOTY, OF DETROIT, MICHIGAN

Letters Patent No. 66,813, dated July 16, 1867.

IMPROVED FOLDING TABLE.

The Schedule referred to in these Letters Patent and making part of the same.

TO ALL WHOM IT MAY CONCERN:

Be it known that I, DUANE DOTY, of the city of Detroit, in the county of Wayne, in the State of Michigan, have invented a new and improved Table for family use; and I do hereby declare that the following is a full and exact description thereof, reference being had to the accompanying drawings, and to the letters of reference marked thereon.

The nature of my invention consists in constructing a four-legged table, so that it can be easily folded so as to occupy but little space when not in use.

Figure 1 is a perspective view of the table with a part of the top cut away so as to show the bolt C.

Figure 2 is a side view of the same when folded.

Figure 3 is an end view of the same.

A and B are cross-pieces, which connect the legs in the ordinary way. Notches *a* and *b*, fig. 2, are cut into the pieces A and B, whose width equals the thickness of the cross-pieces, and their united depth equals the depth of A. When thus made and they are placed at right angles with each other, the cross-pieces will drop into the notches and the upper surfaces be in the same plane, giving an even support for the top D. When the pieces are drawn entirely out of the notches *a* and *b*, they are prevented from being entirely separated by the bolt C, figs. 1 and 2, which passes through both pieces, and has a head on one end and a nut on the other. The bolt C is long enough to permit the pieces A and B to be drawn entirely out of the notches *a* and *b*. The cross-bar B is shorter than A, so that it can be revolved about the bolt C in the same plane as A. The top D is attached to the longer cross-bar A by the hinges *c c*, fig. 2, so that it may be turned down parallel to the plane of the cross-bars, as shown in figs. 2 and 3.

I do not claim a four-legged table, or attaching the top to the cross-piece, but I do claim, and desire to secure by Letters Patent—

The combination of the bolt C, notches *a* and *b*, and the hinged top, when made for joint action, substantially as herein described and for the purposes herein set forth.

DUANE DOTY.
